UNITED STATES PATENT OFFICE.

PROSPER BARDON, OF WACO, TEXAS.

MEANS FOR EFFECTING UPWARD DRAFT IN PRIVIES, COMMODES, &c.

SPECIFICATION forming part of Letters Patent No. 351,731, dated November 2, 1886.

Application filed May 4, 1886. Serial No. 201,049. (No model.)

To all whom it may concern:

Be it known that I, PROSPER BARDON, a citizen of the United States, residing at Waco, in the county of McLennan and State of Texas, have invented new and Improved Means for Effecting Upward Draft in Privies, Commodes, Water-Closets, &c., of which the following, in connection with the accompanying drawings, is a specification.

10 My invention consists in a novel plan of constructing air and gas passages for privies, commodes, water-closets, and other analogous structures, whereby the noxious gases created therein are effectually conducted away from the 15 room or building in which they are used.

In the accompanying drawings I have shown one practical means for illustrating the operation of my invention, in which—

Figure 1 is a vertical central section through 20 an improved privy or commode. Fig. 2 is a top view of the same, the cover of the seat-aperture being removed. Fig. 3 is a diagram illustrating a way in which my invention may be employed in connection with adjacent 25 privies or commodes having united air and gas passages.

A represents a vessel for the reception of 30 fecal matter; B, a seat; C, a draft flue or pipe for conveying the air and gases away from the vessel A.

The vessel A is provided with an upper opening, a, in its top a', which opening is made nearly as large as the diameter of said top. The supporting ledge or chime a'' of the vessel 35 A is made of sufficient height above the top a' to firmly hold therein an annular downwardly-projecting rim, b, of the seat, which rim forms a horizontal chamber below the upper edge of the ledge or chime and between the top a' and seat B. At the rear end of said chamber, and in communication therewith, the draft-flue C is applied, as shown. The aperture or opening b' of the seat is circular, preferably of an oval form, and measures, for a 40 given-sized privy or commode, ten inches by seven inches, while the receptacle A measures twenty-two inches in diameter. The longest diameter of the aperture b' stands centrally between the sides of the seat, and is parallel 45 with the same. The front portions of said opening b' and of the opening a stand about vertically opposite to each other, and closely

behind the rear portion of the opening b' a horizontal foot portion, c, of the draft flue or pipe C is suitably attached to the seat B. This 55 foot portion c opens at c' into the receiving-vessel A with an area of six inches by six and one-half inches, which is also the area of the pipe C, which in length or height should at least be ten feet, in order to be effective as a 60 draft pipe or flue.

In a commode having the above-stated proportions and construction I have found that during and immediately after its use the gases created in the receiving-vessel A rise in the 65 chamber b' through the opening a of top a', and on arriving in said chamber, which, as shown, is below the seat, are met by the atmospheric air at the opening b', which, being heavier than these gases, exerts a pressure upon them, causing 70 them to ascend through the opening c, from whence they, with the atmospheric air, are drawn by the more powerful draft of the flue or pipe C into the foot portion c and up into said pipe or flue. The first rush of the 75 atmospheric air into the receiving-vessel would tend to cause portions of the gases to be crowded up through the opening b' of the seat, and thus in a measure defeat the object of the invention, were not the chamber b' provided, as 80 shown; but this chamber receives such portions of the gases as cannot readily pass into the draft flue or pipe, and retains them below the opening b' until they find their way into the said flue or pipe. After a steady draft 85 has become established in the pipe C the atmosphere of the room containing the commode gradually enters the receiving-vessel through the opening b', mingles with the gases therein, and, thus becoming rarefied to a high degree, 90 rises as a regular current along with the gases from the fecal matter, and passes up into the flue or pipe C and out into the open atmosphere, this going on until the creation of gases in the receiving-vessel ceases.

It is evident from the foregoing description that the opening b' may be left uncovered without danger of any unpleasant odor entering the room in which the commode is placed, and if a cover, as shown, is provided for the seat-aperture its only use would be to hide from sight the opening and contents of the receiving-vessel.

To more plainly point out my invention I

will state that I have found that the proportions of the seat-aperture, receiving-vessel, and draft flue or pipe—that is, the relative horizontal, sectional, or superficial areas of these parts—may be as follows and produce good results: The area of the draft-flue same as area of aperture in seat, and the superficial area of the receptacle greater than the area of aperture in the seat. I also have found that the area of the draft-flue might be from sixty-three to seventy-five per cent. of area of the seat-aperture—that is, if area of said aperture be one hundred superficial square inches the horizontal sectional or superficial area of a draft-flue which is about ten feet high might be from sixty-three to seventy-five square inches, and still beneficial results be secured.

When the horizontal sectional or superficial area of the receptacle is greatly increased, the draft-flue would require to have more than one hundred superficial square inches.

It should be understood that ten feet elevation of the draft flue or pipe is the least or minimum which can be adopted with the best results. The draft flue or pipe could be increased in height and area without any bad results; but a reduction of its area would necessitate increase of its height to compensate for the reduction of area. This change would not be a departure from my invention.

The relative proportions of measurement above stated for the several passages, flue, and receiving-vessel will require to be changed to suit commodes, privies, and water-closets of large or small superficial area. The same proportions of parts as herein given for com-

modes may be adopted when my invention is applied to privies and water-closets instead of to commodes, this having been found by numerous experiments.

In Fig. 3 two commodes are shown, the branch draft-pipes C^2 C^3 of which are united into one pipe, C , which has double the superficial area of a single draft-pipe such as is shown in Fig. 1, while each of the branch pipes has an equal superficial area to said pipe shown in Fig. 1.

I am aware that various plans are known and used for ventilating privies and water-closets; but they differ in operation from my invention, and have not given satisfactory results. I therefore do not claim a commode or privy ventilator, broadly; but

What I do claim is—

In a privy, commode, or closet, the combination of a seat having an aperture about ten inches by seven inches in area, a ventilating draft-flue having a diameter of about six inches by six and one-half inches and a height of about ten feet, and a receptacle having a diameter of about twenty-two inches, the said relative proportions being followed accordingly as the size of the privy, commode, or closet is increased or decreased, substantially as and for the purpose described.

In testimony whereof I affix my signature in presence of two witnesses.

PROSPER BARDON.
